US0D1095820S

(12) **United States Design Patent** (10) Patent No.: **US D1,095,820 S**
(45) Date of Patent: ** Sep. 30, 2025

(54) **PORTABLE INJECTION DEVICE**

- (71) Applicant: **NEMERA LA VERPILLIERE**, La Verpillière (FR)
- (72) Inventors: **Guillaume Cerqueira**, Lyons (FR); **Julien Roux**, Grenoble (FR); **Sébastien Delvalac**, Lyons (FR); **Marc Todesco**, Tignieu-Jamayzieu (FR)

(**) Term: **15 Years**

(21) Appl. No.: **35/513,328**

(22) Filed: **Dec. 21, 2021**

(80) **Hague Agreement Data**

Int. Filing Date: **Dec. 21, 2021**

Int. Reg. No.: **DM/218052**

Int. Reg. Date: **Dec. 21, 2021**

Int. Reg. Pub. Date: **Jan. 7, 2022**

(51) **LOC (15) Cl.** 24-02

(52) **U.S. Cl.**

USPC **D24/113**

(58) **Field of Classification Search**

USPC D24/112-114, 133, 186, 127-131
